UNITED STATES PATENT OFFICE

172,918

SIGNAL LIGHT HOUSING FOR USE ON AUTOMOTIVE VEHICLES

Paul Belokin, Jr., Stickney, Ill., assignor, by
mesne assignments, to Auto Lamp Manufacturing
Company, Chicago, Ill., a copartnership

Application July 1, 1953, Serial No. 25,746

Term of patent 14 years

(Cl. D48—32)

To all whom it may concern:

Be it known that I, Paul Belokin, Jr., a citizen
of the United States, residing at Stickney, in the
county of Cook and State of Illinois, have in-
vented a new, original, and ornamental Design
for Signal Light Housing for Use on Automotive
Vehicles, of which the following is a specification,
reference being had to the accompanying draw-
ing, forming a part thereof.

In the drawing—

Figure 1 is a top plan view of a signal light
housing for use on automotive vehicles, showing
my new design.

Figure 2 is a rear elevational view.

Figure 3 is a front elevational view.

Figure 4 is an end elevational view.

I claim:

The ornamental design for a signal light hous-
ing for use on automotive vehicles, as shown.
